LASTING MACHINES

Ralph E. Pearsall, Gloucester, Mass., assignor to United Shoe Machinery Corporation, Flemington, N.J., a corporation of New Jersey

Filed Mar. 27, 1959, Ser. No. 802,348

4 Claims. (Cl. 12—1)

This invention relates to lasting machines of the type wherein a pair of rotary members are arranged to exert frictional forces on the lasting margin of the stock to be lasted in a direction tending to tension the stock heightwise of a last and in a direction tending to feed the shoe along, the margin of the tensioned stock then being wiped inwardly over and pressed against the bottom of the shoe to cause the lasting margin to be secured to the bottom of the shoe in lasted position by cement previously applied to the bottom of the shoe and/or to the inner surface of the lasting margin. Subsequently to the lasting of a shoe on a machine of this type, the overlasted margin of the stock is subjected to a separate abrading or roughing action in order to condition it for the reception of so-called "bottoming" cement by means of which an outer sole is attached to the bottom of the shoe. It is an object of this invention to avoid the necessity for such a separate abrading and roughing operation by providing a novel and improved lasting machine of the mentioned type in which the lasting and the abrading or roughing operation are simultaneously performed.

With the above object in view, in the herein illustrated machine, which is provided with a pair of rotary members for engaging the opposite sides of the lasting margin of the shoe to be lasted, and with means for so guiding a shoe that these members exert frictional forces tending to tension the stock and to feed the shoe, the peripheral surface of one of the rotary members which engage the inside of the lasting margin is roughened in the usual manner while the peripheral surface of the other of the rotary members is provided with sharpened teeth for abrading the outside surface of the lasting margin, power operated means being provided for driving these members with the last-named member rotating at a considerably higher speed than the other, together with means for wiping the roughened lasting margin of the tensioned stock inwardly over and for pressing it against the bottom of the shoe. More particularly, the rotary members may comprise a pair of rolls, while the wiping means which has a continuous action may include a reciprocating wiper and a continuously operating chain wiper. Preferably, and in accordance with another feature of the invention, a third rotary member having a roughened peripheral surface may be arranged coaxially of the rotary member which has the sharpened teeth, thereby to provide an unroughened portion of the overlasted margin adjacent to the marginal edge of the shoe bottom, and means provided for rotating this third member at the same speed as the member which engages the inside surface of the lasting margin.

The above and other objects and features of the invention will appear in the following detailed description of the preferred embodiment thereof which is illustrated in the accompanying drawings and will be pointed out in the claims.

In the drawings,

Fig. 1 is a view in elevation of the left-hand side of

2

a lasting machine embodying the features of this invention;

Fig. 2 is a view in elevation and at an enlarged scale of the operating elements of the machine as seen from the opposite side of the machine;

Fig. 3 is a detail view of one of the operating elements with a portion thereof shown in vertical section; and

Fig. 4 is a plan view of the operating elements and showing a portion of a shoe being lasted.

10 Referring to these drawings, the operating elements of the machine which is therein illustrated comprise a pair of rolls 10, 12 for tensioning the stock and for feeding the shoe, one of these rolls also being adapted, as will presently appear, to abrade or roughen the outer surface of the lasting margin of the stock being lasted, a reciprocating wiper 14, and a chain type wiper indicated generally by the reference character 16. These operating elements are supported on and driven by mechanism associated with a machine frame construction, indicated generally by the reference character 18, and an auxiliary frame, indicated by the reference character 20. As shown in Fig. 1, these machine frame constructions are supported on the upper end of a column 22 of suitable height. During the lasting operation, the shoe is 25 guided by engagement with an edge gage roll 24 and is held against heightwise movement, in response to the tensioning action of the rolls 10 and 12, by means of a shoe rest 26. As shown in Fig. 3, the roll 10 actually comprises a feed wheel 30 and a roughing roll 32.

30 The feed wheel 30 is secured to the lower end of a shaft 40 by means of a headed screw 42 and has rotatably mounted on a sleeve portion 44 the roughing tool 32. The shaft 40 extends upwardly through a bearing 46, associated with the auxiliary frame 20, Fig. 2, and at its

35 upper end and carries a gear 48 which is in mesh with a drive pinion 50, mounted on the shaft of an electric motor 52, Fig. 1. The roll 12 is mounted on the lower end of a shaft 60 which is journaled in a bearing block 62 formed integrally with an arm 64. This block is

40 guided in a bifurcated portion 66 of the auxiliary frame 20, Fig. 2. At its upper end, the arm 64 is connected to a clevis block 67 which is pivotally mounted, by means of a trunnion 68, in an upstanding bracket 70 on the auxiliary frame 20, Fig. 1. The block 67 also carries a bearing 45 for the upper portion of the shaft 60 and this shaft is connected to the shaft 40 by means of loosely meshing pinions 72, 74. A coil spring 76 tends to swing the arm 64 in a clockwise direction, Fig. 1, thereby urging the roll 12 yieldingly toward the roll 10 to the extent

45 permitted by an adjustable stop stud 80 adapted to engage an abutment 82 carried by the arm, Fig. 2. The tension of the spring 76 may be varied by means of an adjusting lever 84 and locking pin 86, Fig. 1.

50 Secured to the abrading roll 32 is a pinion 90 which is adapted to be driven at a relatively high speed, as compared to the speed of rotation of the feed wheel 30 and roll 12, by means of a gear train including gears 92, 94, 96, 98, 100 from a second electric motor 102, Fig. 2. This gear train is mounted on a carrier bracket 104 associated with the auxiliary frame 20 and the motor 102 has a drive shaft 106 which is connected to the gear 100 through a friction clutch device indicated generally by the reference character 108.

55 The wiper 14 is secured to a slide 110 which is slidably mounted in guideways formed in a block 112, Fig. 2. This block is supported on a bracket 114 which, in turn, is adjustably mounted on the main frame 18, Fig. 1. At its right-hand end the slide 110 is provided with an up- 60 standing arm 120 which is held in engagement with an eccentric 122 by means of a coil spring 124, Fig. 2. As will be apparent, when this eccentric, which is mounted

65

70

on a shaft 126, is rotated, the slide 110 and wiper 14 will be reciprocated.

The shaft 126 is rotatably mounted on the main frame 18 by means including a bearing bracket 130 and has secured thereto a sprocket 132 and a drive pulley 134 which is connected to a third electric motor, or other power source, not shown, by means of a drive belt 136. Pivottally mounted on this shaft is an arm, indicated generally by the reference character 140, which is held yieldingly in the position shown in Fig. 1 by means of a tension spring 142 and abutment screw 144. Journaled in the outer end of this arm on a stub shaft 146 is a second sprocket 148, and trained over these two sprockets is the chain wiper comprising a series of links 149 to each of which is attached a relatively flat wiping member 150, Figs. 1 and 4.

Pivottally mounted on a bracket 160 is a lever 162 having a rounded operating end 164 located beneath a laterally extending portion 166 on the arm 140. Extending between the other end of this lever and one arm 168 of a bell-crank lever having a second arm 170 is a link 172. A foot treadle, not shown, is connected to the arm 170 by means of a link 174, and by depressing this treadle, against the resistance of a return spring 176, the operator may swing the arm 170 in a counterclockwise direction, thereby to elevate the chain wiper 16.

The edge gage roll 24 is rotatably mounted on the upper end of an arm 180 which is secured to the bracket 114, Fig. 1, while the shoe bottom rest 26, which is shaped as shown in Fig. 4, is adjustably mounted on the bearing block 62, by means of screws 182, Fig. 2.

As viewed from the front of the machine, i.e., from the right in Fig. 1, the shafts 40 and 60 are inclined to the right from the vertical, and this angle of inclination may be varied by swinging the auxiliary frame 20 about a trunnion bolt 190, Fig. 1, and then locking it in the desired position of adjustment by means of a clamp nut 192 on the bolt and a clamp screw 194 which is received within an arcuate slot 196 in the main frame 18. The main frame is also pivottally mounted on the column 22 by means of a rockshaft 200, and may be adjusted about the axis of this shaft upon release of a clamp nut 202 associated with an arcuate supporting arm 204. Thus, the main frame 18 and auxiliary frame 20 which is carried thereby may be swung in a counterclockwise direction, Fig. 1, to incline the shafts 40 and 60 upwardly and away from an operator standing in front of the machine.

In use, with the several drive motors running, the operator, after depressing the treadle, not shown, to elevate the wiper 16, introduces the lasting margin L of the stock to be lasted, herein illustrated as the cover of a platform shoe Sh, assembled on a last with a sock-lining S and platform P, the marginal portion of which cover has been coated with a band of cement C, between the rolls 10 and 12, with the bottom of the shoe tipped downwardly away from the wiper 14. Next, as the shoe is swung into a position in which its bottom surface adjacent to the rolls 10 and 12 is substantially horizontal and held in engagement with the shoe rest 26, the treadle is released, thereby permitting the wiper 16 to be held yieldingly in engagement with the lasting margin L as it leaves the rolls.

Now, as the operator supports the shoe and holds its marginal edge in engagement with the edge gage roll 24 and the bottom of the shoe in engagement with the shoe rest 26 and wipers 14 and 16, the shoe will be fed along and the lasting margin of the stock L will be subjected to a tensioning action by the rolls 10 and 12. As the lasting margin of the stock L emerges from between the grip of the two rolls 10 and 12 and feed wheel 30, a narrow portion of it is first wiped inwardly over the marginal edge of the bottom of the shoe by means of the rapidly reciprocating wiper 14, Fig. 4, and immediately thereafter the lasting margin, throughout its entire width, is wiped inwardly over and pressed against the

bottom of the shoe by the continuously acting chain wiper 16.

The roll 12 and feed wheel 30 are driven in opposite directions at substantially the same peripheral speed, 5 which is considerably slower than the speed of the roughing tool 32 and such that the operator has no difficulty in supporting and guiding the shoe being lasted as it is fed along. On the other hand, the roughing tool 32, which is provided with sharpened teeth of any desired shape and arrangement, herein illustrated by way of example as a series of cutting teeth 250 arranged in the shape of a spiral band with a chip clearance space 252 therebetween, is driven at a relatively higher speed. Accordingly, inasmuch as the sharpened teeth 250 cut away or abrade the outermost surface layer of the lasting margin, see 254, Fig. 4, with much less frictional resistance than that afforded by the duller serrations on the roll 12 and feed wheel 30, the shoe travels at a slower speed determined by these two elements. However, while roughing or abrading the surface of the lasting margin, the roughing tool 32 exerts a frictional force on the lasting margin of the stock extending in a direction normal to its axis and in its plane of rotation which force has a component tending to tension the stock heightwise of the shoe and a component tending to feed the shoe, much in the same manner as an ordinary tensioning and feeding wheel. As shown in Fig. 4, that portion of the lasting margin which is engaged by the feed wheel 30 is not roughened or abraded and remains 20 as a narrow safety zone 256 at the very edge of the bottom of the shoe. If for any reason it is desired to extend the roughened area out to the marginal edge of the bottom of the shoe, the feed wheel 30 may be eliminated. In the particular mechanical arrangement herein illustrated, this may be accomplished by decreasing the outer diameter of the wheel portion 30 and extending the tool 32 downwardly thereover.

Having thus described my invention, what I claim as new and desire to secure by Letters Patent of the United States is:

1. A machine for lasting shoes having a pair of driven rotary members mounted on axes which lie in a common plane for engaging between their peripheral surfaces the opposite sides of the lasting margin of stock to be lasted, means associated with said members for so guiding a shoe relatively thereto that frictional forces are exerted on the lasting margin by said rotary members in a direction tending to tension the stock heightwise of the shoe and in a direction tending to feed the shoe along, the peripheral surface of one of said rotary members which engages the inside of the lasting margin being roughened to augment its frictional action and the peripheral surface of the other of said rotary members being provided with sharpened teeth for abrading the outside surface of said lasting margin throughout substantially its entire width, means for driving said first-mentioned rotary member at a predetermined speed, means for driving the second-mentioned rotary member at a considerably higher speed than the other said rotary member, and means adjacent to said rotary members for wiping the roughened lasting margin of the tensioned stock inwardly over and for pressing it against the bottom of the shoe.

2. A machine for lasting shoes having a pair of driven rotary members mounted on axes which lie in a common plane for engaging between their peripheral surfaces the opposite sides of the lasting margin of stock to be lasted, means associated with said members for so guiding a shoe relatively thereto that frictional forces are exerted on the lasting margin by said rotary members in a direction tending to tension the stock heightwise of the shoe and in a direction tending to feed the shoe along, the peripheral surface of the one of said rotary members which engages the inside of the lasting margin being roughened to augment its frictional action and the peripheral surface of the other of said rotary members being

provided with sharpened teeth for abrading the outside of said lasting margin throughout substantially its entire width, means for driving said first-mentioned rotary member at a predetermined speed, means for driving the second-mentioned rotary member at a considerably higher speed than the other said rotary member, and means adjacent to said rotary members for continuously wiping the roughened lasting margin of the tensioned stock inwardly over and for pressing it against the bottom of the shoe.

3. A machine for lasting shoes having a pair of driven rotary members mounted on axes which lie in a common plane for engaging between their peripheral surfaces the opposite sides of the lasting margin of stock to be lasted, means associated with said members for so guiding a shoe relatively thereto that frictional forces are exerted on the lasting margin by said rotary members in a direction tending to tension the stock heightwise of the shoe and in a direction tending to feed the shoe along, the peripheral surface of the one of said rotary members which engages the inside of the lasting margin being roughened to augment its frictional action and the peripheral surface of the other of said rotary members being provided with sharpened teeth for abrading the outside of said lasting margin throughout substantially its entire width, means for driving said first-mentioned rotary member at a predetermined speed, means for driving the second-mentioned rotary member at a considerably higher speed than the other said rotary member, and means including a reciprocating wiper and a continuously operating chain wiper adjacent to said rotary members for wiping the roughened lasting margin of the tensioned stock inwardly over and for pressing it against the bottom of the shoe.

4. A machine for lasting shoes having a pair of driven rotary members mounted on axes which lie in a common

plane for engaging between their peripheral surfaces the opposite sides of the lasting margin of stock to be lasted, means associated with said rotary members for so guiding a shoe relatively thereto that frictional forces are exerted on the lasting margin by said rotary members in a direction tending to tension the stock heightwise of the shoe and in a direction tending to feed the shoe along, the peripheral surface of the one of said rotary members which engages the inside of the lasting margin being roughened to augment its frictional action and the peripheral surface of the other of said rotary members being provided with sharpened teeth for abrading the outside of said lasting margin, means for driving said first-mentioned rotary member at a predetermined speed, means for driving the second-mentioned rotary member at a considerably higher speed than the other of said rotary members, a third rotary member arranged coaxially with the second-named rotary member and having a roughened peripheral surface for engaging the outside of the lasting margin of the stock, means for driving said third member at substantially the same speed as the speed of the first-mentioned rotary member, and means adjacent to said rotary members for wiping the roughened lasting margin of the tensioned stock inwardly over and for pressing it against the bottom of the shoe.
